To all whom it may concern:

Be it known that I, WILLIAM McCALLUM, of Yonkers, in the county of Westchester and State of New York, have invented a new and original Design for Carpets, of which the following is a specification.

This invention relates to a new and original design for carpets and similar fabrics; and it consists in the novel grouping and configuration of parts hereinafter more fully described.

The accompanying photograph illustrates a face view of a carpet having my new design.

The band A contains a series of diagonal stripes, between which are set a series of leafy branches, running diagonally in the same direction as the stripes.

The stripe B contains at its upper portion an ornamentation consisting of the leafy figure d and the figure a, resembling a bunch of flowers, both contained in a panel formed between a vertical band, b, at each side and the horizontal bands A and D at the top and bottom, respectively, the band D at the bottom containing an ornamentation of circular figures with open centers, having a series of arches above them.

The stripe E is ornamented with a series of panels, e, in the form of windows, circular at the tops, each containing a flower-like figure therein and set in a series, alternating with

figures f, each resembling a plant with a central flower set upon a stem growing out of a flower on each side of its base.

The band F, below the stripe B, contains an angular ornamentation resembling the teeth 35 of a saw.

I claim—

1. The design for carpets, consisting of the band A, substantially as shown.
2. The design for carpets, consisting of the stripe B, containing bands b and D and figures d and a, substantially as shown.
